UNITED STATES PATENT OFFICE

133,498

DESIGN FOR A VULCANIZING MOLD

Harold L. Baker, Oakland, Calif.

Application March 17, 1942, Serial No. 106,214

Term of patent 14 years

To all whom it may concern:

Be it known that I, Harold L. Baker, a citizen of the United States, residing at Oakland, county of Alameda, and State of California, have invented a new, original, and ornamental Design for a Vulcanizing Mold, of which the following is a specification, reference being had to the accompanying drawing, forming part thereof.

Fig. 1 is a perspective view of a vulcanizing mold, showing my new design.

Fig. 2 is an end view of the mold shown in Fig. 1.

Fig. 3 is a plan view of the mold shown in Fig. 1.

I claim:

The ornamental design for a vulcanizing mold, as shown.

HAROLD L. BAKER.
